UNITED STATES PATENT OFFICE.

WINFIELD RIPLEY, OF BRECKENRIDGE, COLORADO.

TEETHING-RING.

1,117,093.

Specification of Letters Patent. Patented Nov. 10, 1914.

Application filed July 9, 1913. Serial No. 778,132.

To all whom it may concern:

Be it known that I, WINFIELD RIPLEY, a citizen of the United States, residing at Breckenridge, in the county of Summit and State of Colorado, have invented new and useful Improvements in Teething-Rings, of which the following is a specification.

This invention relates to teething rings and the object of the invention is to provide a ring having a plurality of projecting biting surfaces, the inner or connecting portion of which is thinned out so as to permit the infant to secure a firm grip upon the same and is so curved as to conform with the outline of the jaws.

Further objects of the invention will appear as the following description is read in connection with the accompanying drawing, which forms a part of this application, and in which:

Figure 1 is an elevation of the ring. Fig. 2 is an enlarged detail sectional view taken therethrough.

Referring more particularly to the drawing, 1 represents a ring formed of ivory, celluloid, gutta-percha, rubber or other suitable material having a plurality of projections 2 projecting from the periphery thereof and having a general semi-circular outline, as shown. These projections are so constructed by gradually increasing their thickness from the point of connection to their

outer edge as to give the infant a firm grip upon the projections. The ring also has its periphery recessed at the inner end of each projection, such recess conforming approximately to the outline of the infant's jaws. Extending through and across the ring is a pin 3 upon which is mounted a spacing sleeve 4 adapted to hold the bells 5 in separated relation against opposite sides of the ring. In these rings is a ball 6 of sufficient size to prevent escape through the opening between the bells and which runs around freely, forming in effect a loose clapper which produces an audible signal each time the ring is shaken.

What is claimed is:—

A new and improved article of manufacture comprising a ring having a group of spaced projections of semicircular contour formed integral therewith and extending radially from and surrounding the periphery thereof, said projections being of increased thickness from their inner to their outer edges and having their opposite faces curved to form recesses at their point of juncture with said ring as described.

In testimony whereof I affix my signature in presence of two witnesses.

WINFIELD RIPLEY.
